UNITED STATES PATENT OFFICE

169,065

DROP CHUTE COIN SELECTOR

Mitchell A. Hall, Fort Thomas, Ky., assignor to
 Monarch Tool & Manufacturing Company, Cincinnati, Ohio, a corporation of Ohio

Application June 2, 1951, Serial No. 15,384

Term of patent 14 years

(Cl. D52—3)

To all whom it may concern:

Be it known that I, Mitchell A. Hall, a citizen of the United States, residing in Fort Thomas, Campbell County, Kentucky, have invented a new, original, and ornamental Design for a Drop Chute Coin Selector, of which the following is a specification, reference being had to the accompanying drawings, forming part thereof.

Fig. 1 is a side view of a drop chute coin selector, showing my new design.

Fig. 2 is a side view of the other side of the drop chute coin selector of Fig. 1.

Fig. 3 is a front view of the drop chute coin selector.

Fig. 4 is a rear view of the drop chute coin selector.

Fig. 5 is a top view of the drop chute coin selector.

Fig. 6 is a bottom view of the drop chute coin selector.

That part of the drawing shown in dotted lines forms no part of my design.

I claim:

The ornamental design for a drop chute coin selector, as shown and described.

MITCHELL A. HALL.
